Primary Examiner—Philip S. Hyder
Attorney, Agent, or Firm—Rudnick & Wolfe[57] CLAIM

The ornamental design for a wheel assembly for an article of luggage, as shown.

DESCRIPTION

FIG. 1 is a perspective view of a wheel assembly for an article of luggage showing our new design;

FIG. 2 is a rear elevational view thereof;

FIG. 3 is a right side elevational view thereof;

FIG. 4 is a left side elevational view thereof;

FIG. 5 is a top plan view thereof;

FIG. 6 is a bottom view thereof; and,

FIG. 7 is a front elevational view thereof.

The broken line portions of the drawing disclosure are for illustrative purposes only and form no part of the claimed design.
